UNITED STATES PATENT OFFICE.

ROY V. COLLINS, OF NEW YORK, N. Y., ASSIGNOR TO AMERICAN AUTOMATIC SWITCH COMPANY, OF NEW YORK, N. Y., A CORPORATION OF NEW YORK.

MOISTURE-PROOF PACKING.

No. 908,647.

Specification of Letters Patent.

Patented Jan. 5, 1909.

Application filed February 8, 1908. Serial No. 414,856.

REISSUED

To all whom it may concern:

Be it known that I, Roy V. Collins, a citizen of the United States, and a resident of the borough of Manhattan of the city of New York, in the county and State of New York, have invented certain new and useful Improvements in Moisture-Proof Packing, of which the following is a specification, reference being had to the accompanying drawings, forming a part hereof.

Where mechanism such as is employed in the electrical operation of railway switches, is located in the ground adjacent to a switch, it is necessary to incase it carefully in a moisture proof box so that it shall not become deranged through the infiltration of water or the penetration of dirt. As a general rule, such boxes are provided with a plunger which extends through one of the sides or ends thereof for the purpose of transmitting to the switch the power or motion developed within the box. In such an arrangement it is particularly difficult to so pack the plunger as to effectively keep out the moisture and dirt without at the same time interfering with the proper movements of the switch mechanism; and in any event such packing is difficult to keep tight and in a uniform condition about the plunger, with the result that it can hardly be said to afford such substantial protection to the mechanism inside the box as is desired.

In accordance with the present invention, the motion or power is transmitted from the moisture proof box inclosing the mechanism to be protected, through the medium of a shaft which projects from said box; and a novel form of packing has been devised for the projecting end of the shaft to provide a perfectly water tight and dust proof seal.

The improvements will be more fully described with reference to the accompanying drawings in which,

Figure 1 is a plan view of a sufficient portion of the box, with the improvements embodied therein, to enable the invention to be understood, the cover of the box being removed, and, Fig. 2 is a view partly in elevation and partly in vertical section.

The construction of the box itself is immaterial to the present invention; as illustrated in the drawing, only one end of the box is shown, being indicated by the letter

a, while the other end is broken off. At this end, a plunger, which in the present case forms a part of the core of an electro magnet and which as will be understood is reciprocated by the magnet, is indicated by the letter *b*. It is operatively connected, through arms *c* above and below, with a shaft *d*, journaled at one end in the bottom of the box and with the other end projecting through an inner cover of the box which protects the switch mechanism. The arms *c* are pivoted to the plunger, a pin *e* extending through the free ends of said arms and the plunger for this purpose, and the other ends of said arms are made fast to the shaft *d*, so that as the plunger is reciprocated the shaft will be turned first in one direction and then in the other direction. The projecting end of the shaft is provided with an arm *f* the end of which is secured through a link *g* to the switch indicated at *h*. This arm and link are, for convenience and simplicity in the installation of the switch, provided in a space between the inner cover and an outer cover to the box.

In the cover of the box around the projecting end of the shaft is formed a circular cup *i* and the shaft is provided with an annular flange *k* which extends downwardly into the cup (Fig. 2). When the switch mechanism is placed in operative position adjacent to a switch, the cup is filled half way up or more with quicksilver so that the lower end of the annular flange upon the shaft is immersed therein. In this way it will be obvious that a perfectly water-tight and dust-proof seal is formed which leaves the shaft absolutely free to transmit power to the switch. It will be understood of course that the cup may be secured to the shaft and the projecting flange may be formed as a part of the box without departing from the invention and it will be obvious that other changes may be made in the construction shown and described without avoiding the spirit of the invention.

I claim as my invention:—

The combination with an electric switch mechanism, of a box inclosing said mechanism and having an inner and an outer cover, a shaft in operative relation with said mechanism and journaled in said box, said shaft having one end projecting through the

inner cover into the space between the two covers, a cup formed in the inner cover around the projecting end of the shaft, an annular flange extending into the cup and secured to the shaft, and a connecting arm in said space secured to the projecting end of the shaft.

This specification signed and witnessed this 3rd day of February, A. D., 1908.

ROY V. COLLINS.
